UNITED STATES PATENT OFFICE

166,059

PARKING METER

Adolph E. Yoss, Benton, Ill., assignor to
James W. Menhall, Benton, Ill.

Application March 28, 1951, Serial No. 14,646

Term of patent 14 years

(Cl. D52—3)

To all whom it may concern:

Be it known that I, Adolph E. Yoss, a citizen of the United States, residing at Benton, in the county of Franklin and State of Illinois, have invented a new, original, and ornamental Design for a Parking Meter, of which the following is a specification, reference being had to the accompanying drawing, forming a part thereof, wherein:

Figure 1 is a front elevation of a parking meter embodying my new design.

Figure 2 is a rear elevation of the same.

Figure 3 is a view looking toward one side of the meter.

Figure 4 is a view looking toward the side of the meter opposite that shown in Figure 3.

Figure 5 is a top plan view of the meter.

I claim:

The ornamental design for a parking meter, substantially as shown.

ADOLPH E. YOSS.
